METHOD OF AND APPARATUS FOR FROST
ELIMINATIONCharles H. Tanner and Ernest Watkins, St.
Cloud, Minn.; Jessie M. Tanner administrator
of said Charles H. Tanner, deceased

Application June 2, 1934, Serial No. 728,783

9 Claims. (Cl. 138—32)

This invention relates to the prevention and elimination of frost deposition in gas lines and more particularly to an apparatus and a method for eliminating frost in compressed air, natural and artificial gas as well as other gas lines.

In Patent No. 1,802,683 issued April 28, 1931 to one of us, a method is disclosed whereby deposition of frost in compressed air lines may be prevented. The present invention relates to an improved apparatus and method adaptable for use in conjunction with gas lines of all kinds wherein the gas contains some proportion of water vapor capable of depositing as frost upon a sufficient diminution in temperature.

15 In the drawing:

Fig. 1 shows a side elevation with certain portions in section of one form of apparatus comprising the invention, and

Fig. 2 is a section in line II—II of Fig. 1.

20 Referring more particularly to the drawing, a line or main carrying gas, such as air, artificial or natural gas or other gas containing adventitious quantities of moisture, is shown generally at 5 with means provided at 6 for admitting a vapor functioning to lower the temperature at which a given mixture of water vapor and other gas will deposit frost, as described more fully hereinafter.

For generating the frost preventing vapor, a liquid container 7 is provided of any desired type and size depending upon the quantity of materials to be contained, generally constructed of metal and provided at its upper portion 8 with the upwardly extending conduit 9. A tightly fitting cap 30 covers the upper end of conduit 9, removable upon removal of the locking device 11. The upright conduit 9 serves as filling means for container 7 and a liquid substance in desired amount may be added to the container to the desired height, this height being determined by the sight glass 12 properly positioned upon the container, although other means for determining the level of the liquid in the tank may be used, as for instance, pet cocks placed at different heights 40 upon the container and communicating with the interior thereof. In normal operation the height of the liquid in the container is maintained somewhat below the upper confining portion 8 of the container to permit a vapor collecting and forming portion 13 between the surface 14 of the liquid and the top 8 of the container 7.

The line 9 is connected advantageously by means of a T 15 to the vapor introducing conduit 16 whereby vapors may be led from the top of the 55 container into the gas line 5, a suitable checking

valve 17 being positioned in line 16 to permit flow of vapor from the container to the line.

A suitable heat exchanger is shown at 18 and may comprise any suitable form of heat exchanging apparatus such as the gas heater shown, although any other form of heating apparatus such as oil or electrical heating unit may be employed. Where the device of this invention is used in conjunction with artificial or natural gas lines, heat is provided in the heat interchanger by tapping the gas line as at 19 and leading the desired quantity of fuel through fuel line 20, regulated by valve 21, to the burners 22 of the heat interchanger. Heat interchange is effected by providing a coil 23 adjacent to the fuel burner of the heat interchanger, coil 23 being connected to and having fluid communication with feed line 24 attached to liquid container 7 adjacent the lower portion thereof and in general attached in such fashion that gravity feed may be had of the liquid contained in liquid container 7 to coil 23 of the heat interchanger. To effect gravity feed, liquid container 7 is advantageously elevated above the heater. Heating coil 23 and burner 22 are enclosed in a suitable housing 25 provided with off-25 take flue 26 and a door 27 permitting, in the open position, access to coil 23 and burner 22.

In order to drain spent liquid from liquid container 7 and from the coil 23 of the heat interchanger, a valved drain line 28 is provided adjacent the lower portion of the system so that the system may be drained and cleaned at periodic intervals or at such times as such draining and cleaning is necessary.

30 In order to form the completed system, return conduit 30 is attached to and has fluid communication with the upper portion of coil 23 of the heat interchanger and leads to and has fluid communication with the vapor or upper portion 13 of liquid container 7. Thus upon inserting a material such as an aqueous solution containing a substantial portion of an alkaline substance such as calcium chloride, or other water soluble salts of metals of the alkali or alkaline earth group such as sodium, potassium, calcium, strontium or barium, or ammonium acetate, sodium acetate, or other alkali or alkaline earth acetate, mixed with an alcohol, into the liquid container to a height somewhat above the lower sight level 31 and below upper sight level 32, liquid tends to run into the heating coils, become heated and at the elevated temperature the escaping tendency of the alcohol in the mixture is increased, thereby increasing the vapor pressure of this material 40 causing rapid circulation of the heated substance 45

which debouches into the liquid container 7, the vapor being formed therein passing through exhaust line 16 into the gas main 5 there to mix with gaseous material containing moisture or water vapor.

By providing a disengaging space over the surface 14 of liquid in container 7, unvaporized portions of liquid collect in the container and only the vaporized portion passes off through line 16 to mingle with the gas in main 5. The vapor comprises alcohol and water vapor in small quantities which, when mixed with the water vapor present in the gas, lower the frost point of the mixture to such an extent that such water vapor is not removed as solid frost from the gas but remains therein in vapor form and clogging of valves, pipes and connections with such frost is prevented. Or, where frost has already formed, introduction of vapors formed as above described, causes the frost to pass into vapor form or melt and free or open a line clogged with such frost. Fresh liquid may be introduced into container 7 through line 9 as the level 14 falls indicating consumption of the frost eliminating material.

23 Since in many cases frost elimination of the type described are installed in isolated spots, an enclosure 33 of sufficient size to enclose the heat interchanger 18 and container 7 is provided, preferably raised above the surface on the standards 30 34. The enclosure is provided with a suitable door 35 whereby entrance may be had to the interior of the enclosure. Vents are provided in the top of the enclosure for the feed line 9 and flue 26, and an opening 36 is formed in the bottom thereof in registry with burner 22 to supply air for combustion of fuel at burner 22.

What is claimed is:

1. In apparatus for eliminating frost in gas lines, a gas line, a container for liquid from which a vapor is generated for inclusion in the gas line, a heat interchanger adapted to impart heat to the liquid, means for transporting liquid from the container to the heat interchanger, and separate means for conveying the liquid from the heat interchanger to the container, and means connecting the container and the gas line for conveying vapor from the liquid container to the gas line.

2. In apparatus for eliminating frost in gas lines, a gas line, a container for liquid from which a vapor is generated for inclusion in the gas line, a heat interchanger adapted to impart heat to the liquid, gravity conveying means connecting the container and the heat interchanger for conveying liquid from the container to the heat interchanger, means for simultaneously conveying liquid and vapor from the heat interchanger to the container, and means connecting the container and the gas line for conveying vapor from the liquid container to the gas line.

3. In apparatus for eliminating frost in gas lines, a gas line, a container for liquid from which a vapor is generated for inclusion in the gas line, means for determining the quantity of liquid in the container, a heat interchanger adapted to impart heat to the liquid, means for transporting liquid from the container to the heat interchanger, means for conveying liquid and vapor from the heat interchanger to the container, and means connecting the container and the gas line for conveying vapor from the liquid container to the gas line.

4. In apparatus for eliminating frost in gas lines, a gas line, a container for liquid from which a vapor is generated for inclusion into the gas line, a heat interchanger adapted to impart heat to the liquid, means for transporting liquid from the container to the heat interchanger, means for conveying the liquid from the heat interchanger to the container, means connecting the container and the gas line for conveying vapor from the liquid container to the gas line, and means for draining liquid from the container and heat interchanger.

5. In apparatus for eliminating frost in gas lines, a gas line, a container for liquid from which a vapor is generated for inclusion in the gas line, a heat interchanger adapted to impart heat to the liquid, means for transporting liquid from the container to the heat interchanger, means for conveying the liquid from the heat interchanger to the container, means connecting the container and the gas line for conveying vapor from the liquid container to the gas line, and means enclosing said container and heat interchanger.

6. In apparatus for eliminating frost in gas lines carrying combustible gas, a gas main, a container for liquid from which a vapor is generated for inclusion into the gas line, a heat interchanger adapted to impart heat to the liquid, means for transporting liquid from the container to the heat interchanger, means for conveying the liquid from the heat interchanger to the container, means connecting the container and the gas line for conveying vapor from the liquid container to the gas line, and means connecting the gas main and heat interchanger for supplying the heat interchanger with combustible gas for combustion therein to impart heat thereto.

7. In apparatus for eliminating frost in gas lines, a gas line, a container for liquid from which a vapor is generated for inclusion in the gas line, a heat interchanger adapted to impart heat to the liquid, means for transporting liquid from the container to the heat interchanger, means for conveying the liquid from the heat interchanger to the container, and means connecting the container and the gas line for conveying vapor from the liquid container to the gas line.

8. In apparatus for eliminating frost in gas lines, a container for liquid from which a vapor is generated for inclusion in a gas line, a heat interchanger adapted to impart heat to the liquid, means for transporting liquid from the container to the heat interchanger, and separate means for conveying the liquid from the heat interchanger to the container, and means for connecting the container and the gas line for conveying vapor from the liquid container to the gas line.

9. In apparatus for eliminating frost in gas lines, a gas line, a container for liquid from which a vapor is generated for inclusion in the gas line, means for heating the liquid to raise the vapor pressure of the liquid, means for diverting a portion of the gas in the gas line to said heating means to provide operating fuel therefor, and means connecting the container and the gas line for conveying vapor from the liquid container to the gas line.
